(57) **CLAIM**

The ornamental design for a multi-connection ways hook, as shown and described.

DESCRIPTION

FIG. 1 is a front elevational view of a multi-connection ways hook showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof.
FIG. 7 is a perspective view thereof;
FIG. 8 is a elevational view showing one application of the present design, where those environmental features illustrated in dashed lines are not claimed in the present design;
FIG. 9 is a elevational view showing another application of the present design, where those environmental features illustrated in dashed lines are not claimed in the present design;

FIG. 10 is a elevational view showing a further application of the present design, where those environmental features illustrated in dashed lines are not claimed in the present design;

FIG. 11 is a elevational view showing yet another application of the present design, where those environmental features illustrated in dashed lines are not claimed in the present design; and,

FIG. 12 is a elevational view showing still another application of the present design, where those environmental features illustrated in dashed lines are not claimed in the present design.
